UNITED STATES PATENT OFFICE.

HOWARD D. COLMAN AND BURT A. PETERSON, OF ROCKFORD, ILLINOIS, ASSIGNEES,
BY MESNE ASSIGNMENTS, TO EDGAR S. NETHERCUT, OF EVANSTON, ILLINOIS.

WINDER.

Application filed September 11, 1918, Serial No. 823,075. Renewed September 12, 1928.

This invention relates to means for supporting a yarn mass for rewinding. While the invention is susceptible of various uses, it is particularly applicable to means for supporting a bobbin which is to be rewound in an automatic winder of the type illustrated, for example, in the Colman Patent No. 1,267,977, dated May 28, 1918.

In the accompanying drawings Figure 1 is a view illustrating in side elevation a bobbin-holder embodying the features of this invention. Fig. 2 is a fragmental front view of the parts shown in Fig. 1. Fig. 3 is an enlarged sectional view taken in the plane of line 3—3 of Fig. 1. Fig. 4 is a plan view. Fig. 5 is a vertical sectional view taken in the plane of line 5 of Fig. 2. Fig. 5 illustrates the parts in a different position from that represented in Fig. 2. Fig. 6 is a view similar to Fig. 5 but showing the parts in another position. Fig. 7 is a perspective view of the thread guide. Fig. 8 is a sectional detail.

That embodiment of the invention which is illustrated in the drawings comprises a framework consisting of two side plates 1 and 2 and a top plate 3 rigidly secured together and supported in the framework of the winder in a suitable manner.

Means is provided for supporting an active or running bobbin A and a reserve bobbin B, the end portion of the yarn on the reserve bobbin extending across a bridge C and being held in a clamp D. In Fig. 5 the bobbin A is represented as having been completely unwound. In order to limit the ballooning of the yarn as it leaves the active bobbin, said bobbin is supported within a tubular casing 4, the bobbin being mounted upon a skewer 5. Above the casing 4 are a guide 6 for the running thread and a pocket 7 for the reserve bobbin B. Means is provided for withdrawing the skewer 5 to permit the bobbin A, when wholly or partially unwound, to fall out of the casing 4; and means also is provided for swinging the casing 4 into alinement with the pocket 7 in order that the reserve bobbin may slide into the casing 4. After the reserve bobbin has slid into the casing 4, said casing is returned to operative position and the skewer

is moved into supporting relation to the new active bobbin.

The tubular casing 4 is provided with trunnions 8 (Fig. 2) which are supported in openings 9 in the side plates 1 and 2. Rigid with the casing 4 is a crank arm 10 which is connected by means of a link 11 to a crank arm 12 which is pivotally mounted on the side plate 1. Rigid with the arm 12 is a crank arm 13. A contractile spring 14 connected with the crank arm 13 normally holds the casing 4 in the running position shown in Figs. 2 and 5. The action of the spring 14 is limited by contact of the casing 4 with the transverse member 15 of the framework.

The thread guide 6 consists of a metal plate bent to provide two overlapping edges 16 and 17 which are spaced apart to form a passage 18 through which the thread may pass laterally, said passage leading to an opening 19. When the casing 4 is in running position, the opening 19 is axially alined with the casing.

As shown in Fig. 5, the reserve bobbin pocket 7 is located above and forwardly of the casing 4. The bottom of the pocket 7 is open, the reserve bobbin being supported in the pocket by means of a plate 22 attached to the upper end of the casing 4. When the casing 4 is in running position the plate 22 constitutes a closure or bottom for the pocket 7. As indicated in Fig. 2, the inner wall of the pocket 7 has a slot 23. The lower ends of the slot 23 and the passage 18 are adjacent to each other. In the top plate 3 is a slot 3^a having a flaring entrance. The rear portion of the passage 3^a communicates with the slot 23. The thread of the reserve bobbin having been tied to the exhausted thread and the reserve bobbin having been permitted to slide into the casing 4, the thread of the reserve bobbin passes laterally through the slots 3^a and 23 and the passage 18 and enters the opening 19 as the casing 4 swings into running position.

In order to retain the bobbin within the casing 4 while the casing is in the position shown in Fig. 6, there is provided a stop plate 24 supported in the framework adjacent to the lower end of the tube 4 when the latter is in alinement with the pocket 7.

The skewer 5 is of such dimensions as to pass freely up into the bore of the bobbin a sufficient distance to support the bobbin with the axis of the bobbin coinciding approximately with the axis of the casing 4. The skewer is rigidly secured to the cross bar 25 of a bail 26, said bail comprising the two side arms 27 and 28. The upper end of the arm 27 is pivoted at 29 to a lever 30 which is pivoted to the framework at 31. The forwardly extending arm 32 of the lever 30 is arranged to be engaged by a box cam E on the traveling mechanism (not shown) of the winder.

15 Means is provided for holding the spent bobbin while the skewer 5 is being withdrawn from said bobbin and for guiding the butt of the new bobbin into register with the skewer. This means includes a stripper member 33 having a concave portion 34 adapted to fit upon the lower end of the casing 4. Centrally of the concave portion 34 is an opening 35 to admit the skewer 5. The stripper 33 constitutes the cross-piece of a bail comprising the side arms 36 and 37. The ends of the cross-piece 33 are notched as at 38 (Figs. 2 and 8) to fit slidably upon the side arms 27 and 28 of the outer bail. The upper portions of the arms 36 and 37 of the 20 inner bail have longitudinally elongated openings 39 (Figs. 1, 2 and 3) into which extend pivots 40 fixed to the side plates 1 and 2. It will be seen that the bails are slidable longitudinally of each other, the lower portions 25 of the bails being guided upon each other by means of the notched ends of the stripper 33. The stripper 33 is normally held against the lower end of the casing 4 by means of contractile springs 41 which are anchored to the side plates 1 and 2 and are connected to lugs 42 on the inner bail arms 36 and 37. The outer bail is normally held in the position shown in Figs. 1 and 2 by means of a locking pin 43 located on the lever 30 in position to 30 be engaged by a shoulder 44 on a lever 45, said lever being mounted upon the pivot 40 between the side plate 1 and the inner bail arm 36. The spring 14 is connected to the lever 45 and normally holds the shoulder 44 in place beneath the locking pin 43. The lever 45 is provided above the shoulder 44 with a guide flange 46 arranged to bear against the locking pin 43.

As shown in Figs. 5 and 6, the cam E is arranged to move the lever 30 sufficiently to withdraw the skewer 5 from the spent bobbin and to bring the axis 29 into alinement with the axis 40, the downward movement of the outer bail being limited by engagement of a stop lug 47 (Fig. 8) on the arm 28 with the stripper 33.

Mechanism is provided for swinging the bails forward to remove the stripper 33 and the skewer 5 from their position directly beneath the casing 4 in order to permit the

spent bobbin to fall from the casing. This mechanism includes the lever 45. The spring 14 normally holds said lever in the position shown in Fig. 1 with the lower arm of the lever in contact with a stop pin 48 on the side plate 1. On the lower end of the lever 45 is a pin 49. The traveling mechanism of the winder includes a cam F arranged to engage the upper arm of the lever 45 and swing said lever first to withdraw the shoulder 44 from beneath the locking pin 43 and later, after the cam E has brought the axis 29 into register with the axis 40, to swing the lever 45 to carry the pin 49 against the bail arms 27 and 36, thereby swinging the bails into the position shown in Fig. 6.

The means herein shown for swinging the casing 4 includes a cam G on the traveling mechanism, said cam portion being arranged to move the arm 13 against a stop pin 50.

Assuming the parts to be in the position shown in Figures 1 and 2, the operation is as follows: The cam F moves the lever 45 far enough to withdraw the shoulder 44 from below the locking pin 43. The cam E acting upon the arm 32 lowers the outer bail until the pivot 29 is in alinement with the pivot 40, thereby withdrawing the skewer 5 from the spent bobbin. While the skewer is being removed from the bobbin, the latter is supported against downward movement by the stripper 33, the stripper being held elevated by the springs 41. After the skewer has been withdrawn from the bobbin, the continuing downward movement of the outer bail 26 brings the stop lug 47 (Figs. 2 and 8) into engagement with the stripper 33, whereby the stripper is moved downward to the extent permitted by the elongated openings 39. Contact of the upper end wall of the openings 39 with the pivots 40 limits the downward movement of the stripper and the skewer. The downward movement of the stripper 33 carries the stripper clear of the casing 4. The cam F now moves the lever 45 still farther to swing the bails into the position shown in Fig. 6, thus allowing the spent bobbin to drop out of the casing 4. The cam G then operates the arm 13 to swing the casing 4 into the position illustrated in Fig. 6, whereupon the reserve bobbin slides into said casing. The cam F then leaves the lever 45, permitting the springs 41 to swing the skewer and the stripper into the position represented in full lines in Fig. 5. The cam G then leaves the lever 13, whereupon the spring 14 rocks the casing 4 into the position seen in Fig. 5. The cam E then operates the lever 30 to place the locking pin 43 above the shoulder 44, whereby the skewer is inserted into the bobbin and the springs 41 are permitted to raise the stripper 33 into contact with the lower end of the casing 4. As shown in Fig. 1, the openings 9 are elongated to permit the casing 4 to have sufficient endwise movement

so that it may be lifted by the stripper 33 until it comes into contact with the cover plate 6. There is thus formed a tube relatively tightly closed at both ends. The movement of the casing 4 into place beneath the thread guide 6, and the operation of mechanisms not herein shown cause the thread to move laterally into normal position.

When yarn is being drawn off from the end 10 of a bobbin in unwinding, the ballooning strand of yarn encounters considerable aerial resistance. By enclosing the bobbin in a casing the air in the casing is caused to revolve with the yarn, thereby materially reducing 15 the aerial resistance. This results in a lower and more uniform tension upon the yarn being unwound, and consequently a higher speed of unwinding can be attained with less danger of breakage of the yarn.

20 In the following claims, the term "bobbin" is to be construed to include other generally similar yarn masses. In all other respects, as well, the claims are to be construed as broadly as the prior state of the art permits, 25 the foregoing detailed description having been given for the sake of clearness of understanding of the present embodiment, and not for the purpose of limiting the invention.

We claim as our invention:

30 1. The combination of a bobbin container, a stripper, a bail supporting said stripper, a pivot for the bail, a second bail guided to slide on and swing with the first bail, a skewer on the second bail, a lever pivoted to 35 the second bail, means to move the lever to bring the pivotal connection between the lever and the second bail into register with the pivot of the first bail, and means to swing the bails to carry the skewer and the bobbin into 40 and out of alignment with the container.

2. The combination of a bobbin container, members slidably and pivotally supported above the container, a stripper on one of said members, a skewer on the other member, said 45 stripper and skewer being below the container, means for moving said members longitudinally of the container, and means for swinging said members to carry the stripper and the skewer out of alignment with the container.

50 3. In combination of a bobbin container, members slidably and pivotally supported, a stripper on one of said members, a skewer on the other member, said stripper and skewer being below the container, means for moving the last mentioned member longitudinally of the container, and means for swinging said members to carry the stripper and the skewer out of alignment with the container.

55 4. The combination of a reserve-bobbin pocket, a thread guide, an active-bobbin container movable alternately into operative relation to said pocket and guide, a skewer for supporting a bobbin in said container, means for moving the skewer into and out

of operative relation to a bobbin, and means for moving the skewer into and out of place beneath the container.

5. The combination of a reserve-bobbin pocket, an active-bobbin container movable 70 into and out of operative relation to said pocket, a skewer for supporting a bobbin in said container, means for moving the skewer into and out of operative relation to a bobbin, and means for moving the skewer into 75 and out of place beneath the container.

6. The combination of a bobbin container, a stripper, a skewer adapted to support a bobbin within the container, members supporting the skewer and the stripper, means 80 to move said members longitudinally of the container, and means to swing said members to carry the stripper and the skewer out of alignment with the container.

7. The combination of a bobbin container, 85 a skewer adapted to support a bobbin within the container, a member supporting the skewer, means to move said member longitudinally of the container, and means to swing said member to carry the skewer out 90 of alignment with the container.

8. A winder having, in combination, a container for the bobbin being unwound, a member to close the lower end of the container, 95 a part attached to and supporting said member, and mechanism to swing said part to carry said member away from the container.

9. The combination of a reserve-bobbin pocket, an active-bobbin container pivoted 100 between its ends, means for swinging the container to place one end thereof in receiving relation to the pocket, and a bobbin stop located opposite the other end of the container when the container is in receiving relation to the pocket.

10. The combination of an active-bobbin container pivoted between its ends, means for swinging the container alternately into receiving and operative position, and a bobbin stop located opposite the lower end of the 110 container when the container is in receiving position.

11. The combination of a bobbin container, a stripper, a skewer adapted to support a bobbin in the container, means for moving the skewer and the stripper longitudinally of the container, and means for causing relative lateral movement between the container, on the one hand, and the skewer and the stripper on the other hand. 115

12. The combination of a bobbin container, a skewer adapted to support a bobbin in the container, means for moving the skewer longitudinally of the container and means for causing relative lateral movement between the container, on the one hand, and the skewer, on the other hand. 125

13. The combination of a bobbin container, a member for closing the lower end of the container, said member having an 130

- opening, a skewer adapted to be inserted into said opening, means for removing the skewer from said opening, and means for causing relative lateral movement between the container, on the one hand, and the skewer and the closing member, on the other hand.
14. A winder having, in combination, a thread guide, a container pivoted between its ends to contain a bobbin while it is being unwound, and means for swinging the container into and out of operative relation to the guide.
15. The combination of a thread guide, a tubular container pivoted between its ends below the guide to contain a bobbin while it is being unwound, and means for swinging the container into and out of alinement with the guide.
16. The combination of a reserve-bobbin pocket, a container pivoted between its ends below the pocket to contain a bobbin while it is being unwound, and means for swinging the container into and out of operative relation to the pocket.
17. The combination of a reserve-bobbin pocket, an active-bobbin container pivoted between its ends below the pocket, means for swinging the container into and out of receiving relation to the pocket, and a member connected to the container for closing the lower end of the pocket when the container is out of receiving relation to the pocket.
18. The combination of a reserve-bobbin pocket, an active-bobbin container pivoted between its ends, means for swinging the container to place the upper end thereof in receiving relation to the pocket, a bobbin stop located opposite the lower end of the container when the container is in receiving relation to the pocket, and a part connected to the container for closing the pocket when the container is not in receiving relation to the pocket.
19. The combination of a reserve-bobbin pocket, a thread guide, an active-bobbin container pivoted between its ends, means for swinging the container to move its upper end to and away from the guide and the pocket, a bobbin stop located opposite the lower end of the container when the upper end of the container is at the pocket, and means to close the lower end of the container when the container is in operative relation to the guide.
20. The combination of a reserve-bobbin pocket, a thread guide, and a container for a bobbin which is being unwound, said container being movable alternately into operative relation to said pocket and guide.
21. The combination of a source of bobbin supply, a thread guide, and a holder for a bobbin which is being unwound, said holder being movable alternately into operative relation to said guide and source of supply.
22. The combination of a source of bobbin supply, a thread guide, a holder for a bobbin which is being unwound, and means for causing relative movement between the source of supply and the guide on the one hand, and the holder on the other hand.
23. The combination of a stationary reserve-bobbin pocket and a non-traveling container for a bobbin which is to be unwound, said container being pivotally movable into and out of receiving relation to said pocket.
24. In a bobbin-holder, a tubular casing adapted to contain a bobbin, said casing being pivoted between its ends to swing into receiving and normal position, a member to close the lower end of the casing when in receiving position, and a member to close the lower end of the casing when in normal position.
25. A winder having, in combination, a stationary thread-guide, a stationary reserve-bobbin holder, and means for moving a bobbin from said holder to unwinding position beneath the thread-guide.
26. The combination of a reserve-bobbin pocket, an active-bobbin container mounted below the pocket for movement into and out of receiving relation to the pocket, and means on the container for closing the lower end of the pocket when the container is out of receiving relation to the pocket.
27. The combination of a reserve-bobbin pocket, an active-bobbin container movable to place its upper end in receiving relation to the pocket, a bobbin stop located opposite the lower end of the container when the container is in receiving relation to the pocket, and means on the container for closing the pocket when the container is not in receiving relation to the pocket.
28. The combination of a reserve-bobbin pocket, a thread guide, and a container for a bobbin which is being unwound, said container being pivoted between its ends below the pocket and the guide to swing to and away from the guide and the pocket.
29. A winder having, in combination, a thread guide and a container adapted to contain a bobbin while it is being unwound, said container being pivoted between its ends and arranged when in one position to present the tip of the bobbin adjacent to the thread guide.
30. A winder having, in combination, a support for a reserve yarn mass, a stationary thread guide, and means for moving a bobbin away from the support to an unwinding position wherein the tip of the bobbin is directed toward the guide.
31. In a winder, a reserve bobbin pocket having a top wall containing a thread-guide passage having a flaring entrance, a clamp above the pocket for the end of the thread of the reserve bobbin, and a bridge for said thread between the clamp and the pocket, said bridge being located forwardly of said entrance.

32. A bobbin-supporting structure comprising a reserve-bobbin pocket having a stationary forwardly inclined front wall, an unwinding compartment rearwardly of said pocket, a top wall for said compartment, said top wall having a thread-guide, a clamp above said structure for the end of the thread on a reserve-bobbin, and means forming a passage through which said thread may pass laterally to the thread guide.

33. A winder having, in combination, a reserve bobbin pocket, means forming a space behind said pocket for the unwinding of a bobbin, a guide above said space for the thread being unwound, a clamp above the reserve-bobbin pocket for the end of the reserve-thread, and means forming a guideway through which the reserve thread may pass laterally to the thread guide.

34. A bobbin-supporting structure comprising a reserve-bobbin pocket having a stationary forwardly inclined front wall, a rear wall and a top wall; means below said pocket for supporting a bobbin while being unwound; and a thread guide above said means, said top and rear walls being slotted to guide the thread laterally to said thread guide.

35. In a winder, a stationary reserve bobbin pocket having an opening in its upper end for the manual insertion of a reserve bobbin, a bottom to support the butt of the reserve bobbin, and an inclined front wall against which the bobbin rests, said bottom being withdrawable to permit the endwise discharge of the bobbin.

36. In a winder, a stationary reserve bobbin pocket having an opening in its upper end for the reception of a reserve bobbin and a bottom which is withdrawable to permit the discharge of the bobbin, the top and rear walls of said pocket being slotted to permit the lateral escape of the thread.

37. In a winder, a stationary reserve-bobbin pocket, a clamp above the pocket for the end of the thread of the reserve bobbin, means rearwardly of the pocket for supporting the bobbin during the unwinding of the latter, and a bridge for the reserve thread between the clamp and the pocket and forwardly of said bobbin-supporting means.

In testimony whereof we have hereunto set our hands.

HOWARD D. COLMAN.
BURT A. PETERSON.
